US00D589584S

(12) **United States Design Patent**
Phillips et al.

(10) **Patent No.:** **US D589,584 S**
(45) **Date of Patent:** **** Mar. 31, 2009**

(54) **RODENT TRAP**

(75) Inventors: **Matthew L. Phillips**, Litchfield, CT (US); **Philip Nathan**, West Hartford, CT (US); **Lynn Briggs**, Bristol, CT (US); **Robert Bruno**, Avon, CT (US); **Peter J. Everett**, Collinsville, CT (US); **Thomas Paul Danniger**, Ostrander, OH (US); **Richard Gene Foster**, Powell, OH (US); **Katie Chapman**, Columbus, OH (US)

(73) Assignee: **SMG Brands, Inc.**, Wilmington, DE (US)

(**) Term: **14 Years**

(21) Appl. No.: **29/319,851**

(22) Filed: **Jun. 26, 2008**

Related U.S. Application Data

(63) Continuation-in-part of application No. 29/318,862, filed on May 29, 2008.

(51) **LOC (9) Cl.** **22-05**

(52) **U.S. Cl.** **D22/119**

(58) **Field of Classification Search** **D22/119-124; 43/58, 60-61, 68, 76, 81, 112-114, 124, 43/131, 132.1**

CLAIM

The ornamental design for a rodent trap, as shown and described.

DESCRIPTION

FIG. 1 is a perspective view of a rodent trap showing the claimed design, with a set arm in an unlatched position in accordance with a first embodiment.

FIG. 2 is a front elevation view of the rodent trap of FIG. 1 in accordance with a first embodiment.

FIG. 3 is a rear elevation view of the rodent trap of FIG. 1 in accordance with a first embodiment.

FIG. 4 is a left side elevation view of the rodent trap of FIG. 1 in accordance with a first embodiment.

FIG. 5 is a right side elevation view of the rodent trap of FIG. 1 in accordance with a first embodiment.

FIG. 6 is a top plan view of the rodent trap of FIG. 1 in accordance with a first embodiment.

FIG. 7 is a bottom plan view of the rodent trap of FIG. 1 in accordance with a first embodiment.

FIG. 8 is a perspective view of the rodent trap of FIG. 1, with the set arm in a latched position in accordance with a first embodiment.

FIG. 9 is a perspective view of a rodent trap showing the claimed design, with a set arm in an unlatched position in accordance with a second embodiment.

FIG. 10 is a front elevation view of the rodent trap of FIG. 9 in accordance with a second embodiment.

FIG. 11 is a rear elevation view of the rodent trap of FIG. 9 in accordance with a second embodiment.

FIG. 12 is a left side elevation view of the rodent trap of FIG. 9 in accordance with a second embodiment.

FIG. 13 is a right side elevation view of the rodent trap of FIG. 9 in accordance with a second embodiment.

FIG. 14 is a top plan view of the rodent trap of FIG. 9 in accordance with a second embodiment.

FIG. 15 is a bottom plan view of the rodent trap of FIG. 9 in accordance with a second embodiment.

FIG. 16 is a perspective view of the rodent trap of FIG. 9, with the set arm in a latched position in accordance with a second embodiment.

FIG. 17 is a perspective view of a rodent trap showing the claimed design, with a set arm in an unlatched position in accordance with a third embodiment.

FIG. 18 is a front elevation view of the rodent trap of FIG. 17 in accordance with a third embodiment.

FIG. 19 is a rear elevation view of the rodent trap of FIG. 17 in accordance with a third embodiment.

FIG. 20 is a left side elevation view of the rodent trap of FIG. 17 in accordance with a third embodiment.

FIG. 21 is a right side elevation view of the rodent trap of FIG. 17 in accordance with a third embodiment.

FIG. 22 is a top plan view of the rodent trap of FIG. 17 in accordance with a third embodiment.

FIG. 23 is a bottom plan view of the rodent trap of FIG. 17 in accordance with a third embodiment.

FIG. 24 is a perspective view of the rodent trap of FIG. 17, with the set arm in a latched position in accordance with a third embodiment.

FIG. 25 is a perspective view of a rodent trap showing the claimed design, with a set arm in an unlatched position in accordance with a fourth embodiment.

FIG. 26 is a front elevation view of the rodent trap of FIG. 25 in accordance with a fourth embodiment.

FIG. 27 is a rear elevation view of the rodent trap of FIG. 25 in accordance with a fourth embodiment.

FIG. 28 is a left side elevation view of the rodent trap of FIG. 25 in accordance with a fourth embodiment.

FIG. 29 is a right side elevation view of the rodent trap of FIG. 25 in accordance with a fourth embodiment.

FIG. 30 is a top plan view of the rodent trap of FIG. 25 in accordance with a fourth embodiment.

FIG. 31 is a bottom plan view of the rodent trap of FIG. 25 in accordance with a fourth embodiment.

FIG. 32 is a perspective view of the rodent trap of FIG. 25, with the set arm in a latched position in accordance with a fourth embodiment.

FIG. 33 is a perspective view of a rodent trap showing the claimed design, with a set arm in an unlatched position in accordance with a fifth embodiment.

FIG. 34 is a front elevation view of the rodent trap of FIG. 33 in accordance with a fifth embodiment.

FIG. 35 is a rear elevation view of the rodent trap of FIG. 33 in accordance with a fifth embodiment.

FIG. 36 is a left side elevation view of the rodent trap of FIG. 33 in accordance with a fifth embodiment.

FIG. 37 is a right side elevation view of the rodent trap of FIG. 33 in accordance with a fifth embodiment.

FIG. 38 is a top plan view of the rodent trap of FIG. 33 in accordance with a fifth embodiment.

FIG. 39 is a bottom plan view of the rodent trap of FIG. 33 in accordance with a fifth embodiment.

FIG. 40 is a perspective view of the rodent trap of FIG. 33, with the set arm in a latched position in accordance with a fifth embodiment.

FIG. 41 is a perspective view of a rodent trap showing the claimed design, with a set arm in an unlatched position in accordance with a sixth embodiment.

FIG. 42 is a front elevation view of the rodent trap of FIG. 41 in accordance with a sixth embodiment.

FIG. 43 is a rear elevation view of the rodent trap of FIG. 41 in accordance with a sixth embodiment.

FIG. 44 is a left side elevation view of the rodent trap of FIG. 41 in accordance with a sixth embodiment.

FIG. 45 is a right side elevation view of the rodent trap of FIG. 41 in accordance with a sixth embodiment.

FIG. 46 is a top plan view of the rodent trap of FIG. 41 in accordance with a sixth embodiment.

FIG. 47 is a bottom plan view of the rodent trap of FIG. 41 in accordance with a sixth embodiment.

FIG. 48 is a perspective view of the rodent trap of FIG. 41, with the set arm in a latched position in accordance with a sixth embodiment.

FIG. 49 is a perspective view of a rodent trap showing the claimed design, with a set arm in an unlatched position in accordance with a seventh embodiment.

FIG. 50 is a front elevation view of the rodent trap of FIG. 49 in accordance with a seventh embodiment.

FIG. 51 is a rear elevation view of the rodent trap of FIG. 49 in accordance with a seventh embodiment.

FIG. 52 is a left side elevation view of the rodent trap of FIG. 49 in accordance with a seventh embodiment.

FIG. 53 is a right side elevation view of the rodent trap of FIG. 49 in accordance with a seventh embodiment.

FIG. 54 is a top plan view of the rodent trap of FIG. 49 in accordance with a seventh embodiment.

FIG. 55 is a bottom plan view of the rodent trap of FIG. 49 in accordance with a seventh embodiment; and,

FIG. 56 is a perspective view of the rodent trap of FIG. 49, with the set arm in a latched position in accordance with a seventh embodiment.
